UNITED STATES PATENT OFFICE

2,642,579

DRY TOILET AND SEALER

Elbert H. Posey, Ashville, N. C.

Application September 19, 1949, Serial No. 116,599

2 Claims. (Cl. 4—121)

1

The invention relates to a dry toilet to be used where no sanitary sewer connections are available.

It is an object of the present invention to provide means affording a sanitary and substantially odorless way to immediately transfer waste or fecal matter to a sealed receptacle with a minimum escape of odor and to prevent the escape of any odor whatsoever from the receptacle when placing the waste matter into said receptacle, and to also prevent any odor from escaping out of said receptacle during the period of time required to fill same and until the receptacle is removed, contents disposed of and the receptacle cleansed.

A further object of the invention is to provide means facilitating the handling and proper disposal of waste matter without same being exposed to disease spreading insects, such as house flies, thereby reducing the danger of spreading diseases.

A further object of the invention is to provide means ensuring removal and disposition of waste matter in a clean and odorless manner without polluting the air and spreading filth to surrounding atmosphere.

The accompanying drawings show by way of example an embodiment of the present invention in which

Fig. 1 is a cross section of the device including a receptacle embodying the invention.

Fig. 2 is a side view of the receptacle forming the base of the device and

Fig. 3 is a side view of the upper part of the device consisting of the seat and the bowl.

The device herein disclosed has an operating handle 1 connected with one end to a link or guide member 2 which in turn is attached to cover 5. Handle 1 is further connected at pivot 9 to a stem or rod 3 passing through an opening of cover 5, the opposite end of said stem 3 carrying a plunger disk 4 screwed to said stem 3. The funnel-shaped bowl 6 of the toilet device is connected to an intermediate cylindrical sealing section 7 of reduced diameter. Bowl 6 is connected to the upper end of said cylindrical section 7 by means of wing nut joints 8.

Section 7 is further provided at its lower end with a receptacle cover 9a overlying the open top of the collecting receptacle or container 10. Cover 9a engages at 9b forming a washer seal the upper end of said receptacle 10 and is connected thereto by means of wing nut joints 8a.

Wing nut joints 8, 8a facilitate easy removal of parts 6, 7 and 10 from each other for emptying and cleaning these parts.

2

The cylindrical part 7 is provided at its lower end and in its inner wall with retainer means in the form of a shallow annular groove 11, where a waterproof cardboard disk 12 is normally retained to seal off waste matter from within the receptacle 10. This cardboard disk 12 will be replaced by a fresh disk after use of the toilet. To this end, the plunger disk 4 normally resting approximately at the level of the lower rim of the bowl 6 will be moved into the sealing section 7 and can be pressed down toward the groove 11 whereby a fresh cardboard disk 12 may be moved into groove 11 in lieu of the used one when the toilet was in use.

15 The device operates as follows: In unused state the parts 6, 7 and 10 take the position as shown in Fig. 1 in which the receptacle 10 is odor-proof and sealed by the insertion of a cardboard disk 12 seated in inner wall groove 11, as indicated in dotted lines. The top cover 5 of the toilet seat 6' is closed and the plunger 4 overlies the sealing section 7. Upon use of the toilet device the cover 5 will first be lifted and the user sits on seat 6' while handle 1, stem 3, plunger 4 together with cover 5, are swung back to dotted line position, as seen in Fig. 3.

20 Any waste matter received by disk 12 seated within groove 11 is now pushed into the receptacle 10 in the following manner: Disk 12 seated in groove 11 is forced in downward direction upon closing of cover 5 by means of handle 1 and disk 4 to which a freshly supplied cardboard disk 12 is attached (not shown).

25 If used disk 12 holding waste matter was not as yet removed from groove 11 a pressure of air may be created in section 7 owing to the movement of handle 1 together with plunger 4 carrying said freshly supplied cardboard disk 12 (not shown). This air pressure becomes effective between the just mentioned freshly supplied cardboard disk 12 on plunger 4 and the preceding disk 12 seated in groove 11, so that the latter disk 12 will be forced out of the groove 11 into the receptacle 10 together with the waste material while the freshly supplied disk 12 on plunger 4 will be displaced through the latter to engage with groove 11.

30 Whenever a user rises and feeds a fresh waxed and waterproof cardboard disk 12 into bowl 6, he pulls down handle 1 together with cover 5, plunger disk 4, etc., and thereby forces waterproof disk through the sealing section 7 into the retainer groove 11, where said disk 12 is withheld and seals off any waste matter within receptacle 10.

35 While a preferred embodiment of the invention has been shown and herein described, it will be

understood that the same is capable of modification without departure from the general scope and spirit of the invention as defined in the claims.

Having thus described the invention, what is claimed as new and desired to be secured by Letters Patent, is:

1. A dry toilet and sealer therefor comprising, in combination, a collecting receptacle for receiving waste matter, a cylindrical sealing section of reduced diameter and including an upper end and having a lower end connected to said receptacle, said sealing section being provided with an annular groove in the inner wall surface of said section and adapted to receive a sealing disk in said groove, an upwardly and outwardly flaring bowl including a seat thereon connected to the upper end of said sealing section, a cover for said bowl and pivotally connected to said seat, said cover being provided with an opening, a stem passing through said opening, an operating handle movably connected to one end of said stem, a plunger attached to the other end of said stem and adapted to project into said sealing section, said plunger being movable upon actuation of said handle and upon movement of said stem to pass through said sealing section, whereby waste matter deposited on said sealing disk may be forced with the latter through said plunger into said receptacle.

2. The combination, in a toilet structure having a collecting receptacle, of a handle-operated

plunger with an intermediate section having a cylindrical wall of reduced diameter with respect to said receptacle and connected to the latter thereabove, retainer means provided within said cylindrical wall of said section and adapted to temporarily support a sealing disk within said section and above said receptacle to thereby separate the latter from said section, and a toilet bowl extending upwardly and flaring outwardly from said section, whereby upon operating said plunger waste matter from said bowl when deposited on said sealing disk within said section, may be displaced together with said sealing disk through said plunger from said retainer means into said receptacle, said plunger being adapted to receive a further sealing disk and to move the latter into engagement with said retainer means if the first mentioned sealing disk is displaced from the latter.

ELBERT H. POSEY.
